US00D870655S

(12) **United States Design Patent** (10) Patent No.: **US D870,655 S**
(45) Date of Patent: **** Dec. 24, 2019**

(54) **PORTABLE BATTERY**

(71) Applicant: **SOCIETE TURRIPINOISE DE MECANIQUE**, Saint Didier de la Tour (FR)

(72) Inventor: **Bertrand Vignau-Lous**, Crest (FR)

(73) Assignee: **SOCIETE TURRIPINOISE DE MECANIQUE**, Saint Didier de la Tour (IT)

(**) Term: **15 Years**

(21) Appl. No.: **35/504,372**

(22) Filed: **Oct. 3, 2017**

(80) **Hague Agreement Data**

Int. Filing Date: **Oct. 3, 2017**

Int. Reg. No.: **DM/099334**

Int. Reg. Date: **Oct. 3, 2017**

Int. Reg. Pub. Date: **Feb. 2, 2018**

(30) **Foreign Application Priority Data**

Apr. 6, 2017 (EM) 003844265

(51) LOC (12) Cl. **13-02**

(52) U.S. Cl.

USPC **D13/103**

(58) **Field of Classification Search**

USPC D13/103, 106, 107; 320/104

CPC H01M 2/1072

(57) **CLAIM**

The ornamental design for a portable battery, as shown and described.

DESCRIPTION

1.1 is a perspective view of a portable battery, showing my new design;

1.2 is a rear view thereof;

1.3 is a side view thereof;

1.4 is a top view thereof;

1.5 is a front view thereof; and

1.6 is a side view thereof.

In the drawings, the broken lines are for the purpose of illustrating environment only and form no part of the claimed design.
